UNITED STATES PATENT OFFICE.

ELBERT C. TAYLOR, OF KNOXVILLE, TENNESSEE, ASSIGNOR OF ONE-HALF
TO WM. W. WOODRUFF, OF SAME PLACE.

NAIL-PLATE FEEDER.

SPECIFICATION forming part of Letters Patent No. 236,966, dated January 25, 1881.

Application filed April 27, 1880. (Model.)

To all whom it may concern:

Be it known that I, ELBERT C. TAYLOR, of Knoxville, in the county of Knox and State of Tennessee, have invented certain new and useful Improvements in Nail-Plate Feeders, of which the following is a specification.

My invention relates to improvements in nail machinery of the kind designed for supplying sheets or plates of metal to the cutters which sever the nails therefrom, and particularly to that class of such machinery by which the plates are intermittently advanced and turned to bring uppermost first one side and then the other over and upon anvils or tables upon which the plates are supported while vertically-reciprocating knives or cutters operate to sever the nails from the plate ends by oblique cuts.

My object, mainly, is to provide means for uninterruptedly supplying and feeding forward the plates, one length after another, to the knife or cutter, which is continuously operated.

My object, further, is to provide improved mechanism for operating the nail-plate-feeding devices, and, generally, to improve the machine in details or minor features.

The subject-matter claimed will hereinafter be designated, after first describing my improvements in detail.

In the accompanying drawings, in which the anvil or plate-support and the cutter are omitted, all my improvements are represented as embodied in the best way now known to me. Obviously some of the essential features of my invention may be used without others of the devices, and the details of construction and arrangement may be modified somewhat.

Figure 1 is a side elevation of the machine with the main or driving shaft in section, and parts not essential to an understanding of this invention omitted. Fig. 2 is a transverse upright section through the driving-shaft end of the machine, on the line 22 of Fig. 1, but with some of the parts shown in different positions. Fig. 2a is a transverse section on the lines 22a of Figs. 1 and 2. Fig. 3 is a side elevation of devices intermediate the driving-shaft and nail-plate-handling mechanism, for reversing the motion or changing stroke. Fig. 4 is a

view, partly in side elevation and partly in longitudinal section, on the line 44 of Fig. 15, of the nail-plate-handling mechanism, its supports, and immediate connections. Fig. 5 is a vertical transverse section on the line 55 of Fig. 4. Fig. 6 is an elevation as seen from the side opposite that represented by Fig. 4. Fig. 7 is a side elevation of the oscillating nail-plate-carrying hollow cylinder or inside rocking tube, detached from its housing or outer cylinder. Fig. 8 is a view, partly in plan and partly in longitudinal and horizontal section, through the nail-plate-handling mechanism, on the line 88 of Fig. 9. Fig. 9 is a vertical longitudinal section on the lines 99 of Figs. 8 and 14. Figs. 10, 11, 12, and 13 are transverse sections, showing some parts in end elevation, on the lines 1010, 1111, 1212, and 1313, respectively, of Figs. 4 and 8. Fig. 14 is a view, partly in end elevation and partly in vertical section, in two planes, as indicated by the line 1414 of Fig. 4. Fig. 15 is a plan view, showing parts which support the nail-plate-handling mechanism.

The nail-plate-handling mechanism is adjustably and detachably mounted on a frame or table, A, supported above and at the side of, or projecting laterally from, a standard or upright post, B. The table is adjustable upon or relatively to the post, so that the nail-plates may be caused to travel properly to a suitable anvil and cutter, the positions of which relatively to and operations in connection with my improvements will readily be understood farther on. The post B is suitably fastened to a base-plate or to a floor by feet or legs b—four in number in this instance—above and from between which it projects. The post is vertically slotted for an adjustable angle-piece or block, B', which is guided by the slot as it is moved up or down and held against vibration. A screw, b', passing through the top of the post and working in a tap in the upper or block part, B', of this angle-piece, serves to hold it at any desired elevation, while a cap, B'', fastened by the screw b'' to the block, prevents the latter from moving inward or out of the guideway in the post at one side. The downwardly-projecting arm or shank part B' of this angle-piece bears, and during adjust-

ment works up and down, against the inside of the post or the side opposite that against which the cap B^2 bears. Thus, while the angle-block may be detached readily its accidental displacement is prevented. As the main strain on the block and its shank is downward the screw b' serves to hold it at the desired elevation, and this screw is aided in its work by the pressure of the cap against the post 10 when screwed tightly in place.

To adjust the main table A vertically independently of the adjustment of the block B' , the table is connected with said block by way of a plate, A' , and slotted down-hangers or 15 bracket-arms $A^2 A^2$. A screw-bolt, a , passes through the slots of these brackets into taps in the plate, and serves, when the parts are properly adjusted and the screws tightened, to hold the table at the height desired. The 20 plate A' is pivoted to the block B' at a' , and is provided with a curved slot and a set-screw, a^2 , passing through the slot into the block. In this way the table may be rocked to and fro slightly, to level it and adjust it relatively to 25 the anvil and cutter. A rounded shoulder at the base of the adjustable plate bears in a seat at the angle or junction of the block B' and its shank B^3 , thus supporting the pivot against end-thrust of the plate.

30 To adjust the nail-plate-handling mechanism laterally, it is mounted on the main support or table A, by way of an upper or supplementary table, C, provided with curved guide-flanges or screw-attached shouldered seg- 35 mental plates $C' C'$, working in a guideway formed by a transverse slot in the table A, the front and rear walls of which slot are of curvature corresponding to that of said plates. A threaded rod or long bolt, C^2 , having a polygonal head or crank, so that it may be turned by 40 a wrench or by hand, works through a nut or threaded stud, c , attached to the under side of the supplementary support C. This adjusting-rod C^2 turns in, but has no endwise movement through, a sleeve-bearing, c' , fast to the 45 main table A.

It will readily be understood that by turning the adjusting-rod the supplementary table and parts supported by it will be moved laterally, the movement imparted being a compound vibratory and bodily sidewise movement, the motion sidewise being greater at the heel end of the table than at the front end.

Before describing the nail-plate-handling 55 mechanism or the devices for feeding and turning the nail-plates, I will describe the means which I deem preferable for operating such mechanism.

A driving-shaft, D, mounted in any proper 60 way in suitable bearings, is provided with an eccentric, D' , to which the ordinary straps or sectional encircling band couples one end of a connection-rod, D^2 , made in two parts, which are jointed at d . The connecting-rod works, 65 at its outer or lower end, in suitable guides shown as formed by beveled lapping lips or

cleats d' on an upright, E. (See Fig. 2^a.) The jointed end of the connecting-rod moves in a fixed path or straight vertical line in its guideways at the back of this upright or post 70 E, against which it is held by the lips. The post has an elongated slot, d^2 , through it, in which is guided a vertically-working short stud, d^4 , on the connecting-rod, upon which stud is pivoted a peculiarly-shaped tappet, d^3 , of approximately lozenge shape. The upper or heel end of this tappet is curved or rounded off alike on both sides, while its lower part or point is wedge-shaped, both sides being inclined from or near the center, where 80 the curvature of its sides ceases, to its extreme end or wedge-like point. A peaked guide-block or wedge-like tappet-controlling stud, e , projecting from the post E, is located beneath the tappet and in the vertical plane of 85 its pivot or axis of oscillation and the outer surfaces or faces of the tappet, and its guide stud are flush or in a common vertical plane. A peculiarly-shaped vibrating double cam or yoke, E' , surrounds the tappet d^3 and stud e . 90 The camway in this cam-yoke is at bottom shaped correspondingly, or nearly so, with the stud, and the upper or main part of this yoke is partly curved and partly inclined, so as to conform to the curved and inclined sides 95 of the tappet. At the junction of the tappet part and the stud part of the cam it is considerably contracted in width, as between the shoulders or points $e' e'$. A lever-shank or 100 vibrating rod, E^2 , is formed with or rigidly connected to the cam-yoke, and a pivot, e^2 , secures the yoke at its junction with the shank to the post E.

In operation the cam and its shank or lever are oscillated or vibrated vertically about 105 their pivot as the driving-shaft revolves continuously in one direction, as will now be explained.

Starting, say, with the parts occupying the position shown in Fig. 2, and in full lines in Fig. 3, at which time the connecting-rod D^2 is at or about the finish of an inward or upward stroke, the point of the tappet rests against the inclined wall of its cam-guide at the right side and slightly above the shoulder 110 e' , the heel of the tappet is borne upon by the upper right-hand part of the cam-wall, and the right side of the guide-stud or tappet-controlling block e is borne upon or closely approached by the right wall of the lower part 115 of the cam. As the connecting-rod moves outward or downward the tappet strikes at its point against the stud near its peak, glides downward, and is wedged in forcibly between the inclined sides of the stud and the adjacent wall of the cam, thus rocking the shank or lever E^2 to the left and the cam to the right at its top, so that the parts assume the 120 positions represented by dotted lines in Fig. 3 by the time the outward stroke is completed. 125 Upon the reverse or inward stroke the tappet moves up to a position on the opposite or left-

hand side of the cam-yoke, and is brought to a short pause with its point above the left side of the block e , ready to be wedged in between it and the left side of the cam-track next it upon the outstroke, (shown as completed in Fig. 1,) and so the operation is repeated as the main shaft is kept in motion. It should be noticed that there is a slight pause between the vibrations of the cam and its shank or lever in the opposite directions. In this way there is pause long enough for the cutter to act on the nail-plate, when advanced, as hereinafter will be explained.

The vibrating shank or lever-arm E^2 works between the feet or legs ff' , by which the slotted post E is supported and firmly secured in position. An extensible or lengthwise adjustable pitman, F , is pivoted or pin-jointed, as at f^2 , to the end of the arm E^2 , and at its opposite end the pitman is similarly jointed to the lower end of a long vibrating arm or lever, F' , fulcrumed on the shank of the slide-block, as presently described.

The pitman may be adjusted in length to suit the adjustments of the slide-block and its shank by means of the slots g g' and set-screws or pinch-nuts g' g'' , connecting its two parts in a well-known way. The vibrating arm F' is pivoted at g^2 to the lower end of the shank B^3 of the adjustable block B' , and is slotted or link-shaped at its upper end, G , to engage a rocking block or turning arm, G' , secured about a short fixed stud or pin on a sliding block, G^2 , traveling, when in operation, to and fro in a guideway or slot, h , at the side of a non-turning casing or outer hollow cylinder, H , for the nail-plate-handling mechanism.

An inner oscillating hollow cylinder or rocking tube, H' , which has no endwise movement in its casing H , is provided with a curved groove or camway, h' , which is of about half-spiral form or extends half-way, or a little more than this, round the tube. This way may either be formed as a groove between lands, or as shown in Fig. 7, where the way, instead of being cut into the tube, is between ribs. A straight groove or way, h^2 , with which the curved way communicates at one end, is also provided in the oscillating tube. A round pin or roller, h^3 , on the reciprocating block G^2 , travels in the curved way h' as said block is moved back and forth by the operation of the arm F' . A shoulder, g^4 , on the sliding block G^2 , traverses a straight slot, g^3 , in the non-oscillating case or outer cylinder, as clearly shown in various figures of the drawings.

The supporting-cylinder or outer casing, H , is hinged at or near its heel or front end to the supplementary table C by short downwardly-projecting arms or lugs I I' , through which, as well as through bearings I' I' , a pivot-pin, I^2 , passes. The cylinder has sufficient vertical play as it vibrates about its pivot to raise the nail-plate for turning it, as will be understood farther on, and during the various movements imparted to the nail-plate-handling mechanism

the link G of the lever F' slides either vertically on the block G' , or the block moves endwise in the lever-link without being cramped. This lever vibrates in the slot I^4 in the main 70 table.

Removably attached to the receiving or heel end of the oscillating inner cylinder is a flaring mouth or guide, J , for facilitating the insertion of the strips or nail-plates j . This flaring mouth-piece partially overlaps the end of the inner tube and abuts against an annular shoulder thereon and terminates close to or against the inner end of the outside cylinder. The forward or outer end of the outside cylinder terminates at the annular shoulder or abruptly-enlarged part J' of the inner cylinder, and the bearings for this inner cylinder are formed by the collars or annular enlargements J^2 J^2 at the opposite ends, as shown. The short 80 end bearings thus provided, as plainly shown in Figs. 7, 8, and 9, are preferable to bearings the entire length of the shell, as they may readily be kept lubricated and create but little friction as the inner tube is oscillated in the 85 outer one, with its camway walls or ribs free therefrom.

A conducting passage or way for the nail-plates is provided by two bars or long plates, K K' , the one above the other, with the guideway or passage between them, and shown as formed by a groove in the lower plate covered by the upper plate; but a half-groove may be made in each plate. The plates are secured by their beveled shanks or heel ends to the top 95 and bottom of the inner tube by screws k , so as not to offer any obstruction to the insertion and free travel of the nail-plates. The upper plate or bar is made in two parts, the outer portion being cut away or made quite thin at 100 K^2 , and secured to the lower plate by screws k' . The object of dividing this upper plate and cutting it out is to render it somewhat yielding, to cause the upper one of a pair of intermittently-operating nail-plate-feeding- 105 rolls, L L' , to bear with sufficient pressure upon the nail-plate to gripe it for feeding, and yet accommodate for inequalities in the thickness of the metal. Obviously, instead of so forming the upper plate, the ordinary spring-bearings or yielding housing might be employed for either or both rolls. The bearings for the axes of these rolls are mounted, respectively, 110 on the plates K and K' .

At the delivery or outer end of the guide- 115 plates there are two clamping slotted plates, k^2 k^2 , between which the nail-plate passes and is held on the way to the anvil and cutter. The give of these plates facilitates the proper presentation of the nail-plate to the anvil, and 120 when a plate has been nearly used up, and its rear end has passed beyond the feed-rolls, it is presented to the anvil until nearly or quite all utilized.

An annular block or ring, M , rigidly at- 125 tached to the ends of the plates K K' , and provided with a wiper or cam-projection, m ,

works in a guide-frame or forked bracket, M', at the outer end of the supplementary table C. The forks of the bracket are slotted for the cam to move in, as the ring-block, which is of greater width than said cam, is turned in the space between the forks and bears against them. When the cam is undermost it rides upon the bottom of the bracket, and lifts the plates K K', the cylinders, &c., by tilting them upon the pivot I'. A spring, m', acting upon the rolling block or ring M and its cam keeps the said block or its cam down upon the bottom of the bracket, as will readily be understood. This spring is coiled about a pin attached at its base to a cross-piece or follower, m², working in the slots of the bracket-arms. The spring bears at its lower end on this follower, to keep it pressed on the rolling block, and at top bears against a cross-piece, m³, detachably fastened to the bracket-arms and provided with a guide-hole for the pin about which the spring is secured.

From the above description it will be understood that as the lever F' is rocked on its fulcrum g² by the operation of the pitman F, and the slide-block G² reciprocated, the oscillating cylinder H' and parts carried thereby are given a half-turn, first in one direction and then in the other, one turn being to the right and the other to the left, or vice versa. As the nail-plate is turned to bring uppermost its opposite sides, alternately, the wiper or cam m elevates it, raising it highest when edge down to free it from the anvil, and presenting it flatwise and in the lowest position to be acted on by the cutter, which makes the usual diagonal cross-cuts. It will be seen that neither of the cylinders has any longitudinal reciprocation or endwise movement in action. The nail-plate s are fed along with their adjacent ends abutting, a fresh plate taking the place of the one in advance of it as soon as cut up.

Suitable mechanism for feeding the plates step by step, the proper distances for severing a nail at each cut, through any given plate except the waste or end cuts, will now be described.

An end ring, short tube, or cylindrical shell, N, is formed with or firmly attached to and projects from the annular shoulder J' of the inner oscillating cylinder, H'. A drum, N', is mounted loosely within or so as to turn independently of the shell or ring. This drum is mainly inside the ring, projecting from it slightly at its outer end, where the drum is enlarged by the flanged annular shoulder n, with which enlarged part of the drum is mounted fixedly an internally-toothed spur-gear, n'; or the spur-teeth may be formed, as shown, directly upon the inside of this flange or annular enlargement of the drum. The drum is mounted or supported in the shell by bearing-blocks attached by screws to the shell and fitting in an annular groove in the drum. A ratchet-wheel, O, is loosely mounted upon a sleeve or inwardly-extending thin portion of

the drum close to the shoulder J'. (See Figs. 8, 9, and 12.) A coiled spring, O', wound over and over, is attached at one end to the drum-sleeve and at the other to a stud, o, on the ratchet, and occupies a position between the ratchet and the main or thick body part of the drum.

A rocking and yielding or spring pawl, P, for engaging the ratchet, is pivoted to the outer non-turning shell or main hollow cylinder H, and when acting on the ratchet projects at its nose through a slot, p, in the side of the ring N.

A spring-controlled rocking pawl, Q, pivoted on a lug on the shell or on the shoulder J' of the oscillating cylinder, works through a slot, q, in the top of the shell, to engage the ratchet-wheel. The hollow or circular opening through the drum is large enough to allow the guide-plates K K' to turn freely in operation.

The internal toothed gear, n', meshes with a pinion, R, fast on the inner end of a shaft, having a worm or screw gear, R', upon it, and meshing with a worm-wheel, R². The worm-shaft is shown as mounted in bearings r r on the upper guideway-plate, K, through which the nail-plates are fed. It would, however, be preferable to have these bearings r r secured to and project upward from the bottom plate, K', thereby avoiding play of the worm-shaft as the upper plate, K, yields. This yield, though very slight, might possibly interfere with accurate working of the gearing.

The worm-driven wheel R² is fastened on one end of the shaft which carries the lower feeding-roll, L. This shaft turns in proper bearings in the lower guideway-plate, K', and the roller fast to it projects through a slot in said plate to engage the nail-plates.

The proper amount of feed at each forward movement of the nail-plate is regulated by a stop motion or suitable escapement mechanism, by which the operation of the feed-rolls is intermittent. I prefer the mechanism now to be described.

A ratchet or escape wheel, S, is fixed to the shaft of the lower roll, at the end thereof opposite that to which the worm-wheel R² is attached. The pallets or toothed arms t t of a vertically-rocking lever, T, act upon the escape-wheel teeth. Adjustable stops U U (shown as formed by set-screws passing up through the supplementary table C) are alternately struck at the proper times by the opposite end of a cross-head, V V', of the lever, to rock on its pivot and allow the wheel to turn one tooth, which admits of the feeding forward of the nail-plates.

In operation, as the vibrating lever F' is caused to move the slide-block G² and its connections back and forth, and thus give the intermittent and reverse oscillations to the cylinder H', as before explained, the point or nose of the pawl P on the stationary or outer cylinder slides, for a portion of the time consumed during each complete reciprocation or to-and-fro movement of the slide-block, upon the out-

side of the ring or shell N. While the pawl P is so working outside the shell, the pawl Q, having the motion of the oscillating cylinder, projecting into the ring N through the slot for it, engages the ratchet O, to prevent its turning or reverse movement. Near the completion of the instroke of the lever F', and of the traverse of the slide-block G² toward the receiving end or mouth J of the cylinder, the 5 nose of the pawl P will enter its slot p, as shown in Fig. 12, engage the ratchet O, and for a short time, during the finish of the oscillating movement of the inner cylinder, will stop the motion of the ratchet, while the inner 10 cylinder and the shell N continue their rotation, thus winding up the ratchet-spring, the result of continuing the motion of the cylinder H', and the shell after stopping the ratchet's motion being equivalent, as affecting the 15 spring, of stopping the oscillatory motion of the cylinder and shell and causing the pawl to impart rotary motion to the ratchet in a direction such as to act upon this spring O' with a tendency to wind it up or compress its coils. 20 The coiled thrust-spring p' about the shank of the pawl is of a strength great enough to hold the pawl P up to its work against the resistance of the spring O', and yet will admit of such endwise movement or slight yield of the 25 pawl as is necessary to prevent straining or breaking the spring. At each time the pawl is acting on the spring the escape-wheel S makes one of its partial revolutions, thus allowing the train of gearing operated by the 30 spring to actuate the feeding-rolls. The operation of the spring O' upon the feeding devices takes place, it will be understood, about the finish of each partial turn, or twice for every complete oscillation or rocking movement, once 35 to the right and once to the left, while the pawl P acts only once during such time—viz., when the cylinder H' is turned in that direction which would be toward the left hand viewed from the mouth or receiving end of the 40 apparatus. It should here be noticed that engagement with the moving ratchet-wheel O of the pawl P will prevent further rotation of this wheel; and the continued rotary motion of the inner cylinder, H', which motion is, of 45 course, imparted to the plates K K', which are secured to this cylinder, and also imparted to the feed mechanism carried by the plates, will wind up the spring O' as the drum N', to which one end of the spring is attached, has 50 imparted to it the continued rotary motion of the inner cylinder by connecting with the feed mechanism. The tendency of the spring to unwind is resisted in obvious ways by the escapement mechanism until the actuation of 55 this mechanism, which results from the contact of one of the arms of the lever T with its stop, as already explained.

To allow the pawl P to swing or rock sufficiently to enter and leave the slot in the ring, 60 a spring, p², passes through a slot in its pivot, between its bearing-lugs on the cylinder, and

acts with a tendency to rock the pawl-nose into its slot. The spring yields to allow the pawl-nose to ride out and travel upon the ring when not to engage the ratchet-wheel. The pawl, 70 it should be understood, acts upon the ratchet-wheel of spring O' so as to cause the spring to be wound up at each time amply enough for two actuations of the escapement mechanism feeding devices—that is to say, at the time of 75 every alternate action of the feed mechanism the spring is wound up to compensate not only for the unwinding or force expended then, but also for the intermediate actions. This automatic winding of the spring enables the 80 machine to be kept in operation as long as desirable, and to supply nail-plate after nail-plate without stoppage to wind up or set the spring.

When it may be desired to stop the motion 85 of the inner cylinder, H', and the feed of the nail-plates, the pin or roller h³ of the slide-block G² may be thrown into the straight way or groove h² simply by turning the oscillating cylinder, by hand, slightly to the left, when this 90 roller has completed or is about to finish one of its oscillations to the left. When so turned, the slide-roller will, on the outstroke of the lever and movement of the block toward the anvil, travel the straight groove and continue 95 to reciprocate in it until, by a hand-movement of the oscillating cylinder, the reverse of that to throw out of operation is given at the end of an inward stroke of the slide-block.

I claim as of my own invention—

1. The combination of the table-supporting post, the vertically-adjustable slide-block, the pivoted adjustable plate on the slide-block, and the table secured to said pivoted plate, substantially as and for the purpose hereinbefore 105 set forth.

2. The combination, substantially as hereinbefore set forth, of the slotted table-supporting post, the slide-block adjustable in the post-slot, the rocking plate pivoted to said block, 110 the table, and its slotted arms adjustably secured to the pivoted plate, for the purpose described.

3. The combination of the slotted main table, the supporting-post therefor, means essentially 115 such as described for adjusting said table relatively to its post both vertically and by rocking, and the supplementary table adjustable transversely of the main table in the slot thereof, substantially as and for the purpose 120 hereinbefore set forth.

4. The combination, substantially as hereinbefore set forth, of the table-supporting post, the adjustable slide-block having the downwardly-projecting arm or shank, the lever for 125 operating the nail-plate-handling mechanism pivoted to said shank, and the pitman for vibrating said lever.

5. The combination, substantially as hereinbefore set forth, of the jointed pitman, the 130 table-supporting post, the vertically-adjustable slide-block having the downwardly-projecting

arm or shank, the adjustable rocking plate pivoted to said slide-block, the table adjustably secured to said pivoted plate, and the vibrating lever for actuating the nail-plate-handling mechanism, pivoted to the slide-block shank and operated by the pitman.

6. The combination, substantially as hereinbefore set forth, of the vibrating yoke having the double camway or upper and lower communicating cam-slots, the pivoted reciprocating wedge-pointed tappet working in said yoke, with its heel alternately acting against the opposite sides of the yoke or upper cam-walls thereof, and the fixed peaked stud or wedge-block in the lower part of the yoke, between which block and the narrowed part of the yoke at the junction of the upper and lower camways the wedge-point of the tappet works alternately at opposite sides, for the purpose described.

7. The combination, substantially as hereinbefore set forth, of the eccentric, the jointed connecting-rod, the slotted post by which the connecting-rod is guided, the pointed tappet pivoted to said rod by a stud working in the post-slot, the wedge-block fixed to the post beneath the pivot of the tappet, the double cam-yoke surrounding the tappet and wedge-block, and the pivoted yoke shank or lever connected with the pitman.

8. The combination of the non-turning vertically-vibrating non-reciprocating casing or outer cylinder having the longitudinal slot, the oscillating non-reciprocating inner cylinder having the single straight way corresponding with the slot in the outer cylinder and the single curved way communicating with said straight way, the reciprocated stud or roller adapted to work in either of said guideways, and nail-plate-feeding mechanism actuated during the oscillation of the inner cylinder when its curved way is engaged by said stud, and thrown out of operation when the stud works in its straight way, substantially as and for the purpose hereinbefore set forth.

9. The combination of the non-turning non-reciprocating main or outer cylinder, pivoted to vibrate vertically, the oscillating non-reciprocating inner cylinder supported in said main cylinder and provided with the curved guideway, the reciprocating block working in a guideway in the outer cylinder and having a stud or roller working in the curved way of the inner cylinder, and the vibrating lever provided with a link or slot for actuating said block and roller, substantially as and for the purpose hereinbefore set forth.

10. The combination, substantially as hereinbefore set forth, of the non-reciprocating vertically-rocking outer cylinder, the oscillating cylinder supported therein and having no movement endwise thereof, the grooved bars secured to and projecting from the inner cylinder and forming the nail-plate passage-way, the ring-block and its cam secured to the outer

end of the nail-plate passage-way, and the slotted frame or forked bracket in which said ring-block and cam work, for the purpose specified.

11. The combination, substantially as hereinbefore set forth, of the transversely-adjustable or supplementary table, the outer non-reciprocating and non-turning cylinder pivoted at or near its heel to the table, the inner non-reciprocating oscillating cylinder, and the cam secured to the bars projecting from the oscillating cylinder and in which the nail-plate passage-way is formed, for the purpose described.

12. The combination, substantially as hereinbefore set forth, of a support or table provided at its outer end with the guide-frame or bracket having slotted arms, the non-reciprocating cylinder pivoted at or near its heel end to said support and having no axial or turning motion, the inner non-reciprocating oscillating cylinder, the ring-block oscillating in the bracket and between its arms, the cam on said block working at times in the slots of said arms and at times bearing against the bottom of the bracket, bars, or plates, through which the nail-plates are fed, secured to and projecting from the oscillating cylinder and having the said ring-block and cam fixed to them, and intermittently-acting feed-rolls for thrusting forward the nail-plates at each oscillation of the inner cylinder, as described.

13. The combination of the outer cylinder, the inner oscillating cylinder, the nail-plate passage-way or grooved plates secured to and projecting from said inner cylinder, the feed-rolls, the drum loosely mounted at the outer end of the inner cylinder and within a shell or ring attached thereto, the coiled spring secured at one end to said drum, the ratchet-wheel to which the other end of said spring is secured, the pawl on the outer cylinder working through a slot in the cylinder-ring, at intervals, to engage the ratchet-wheel, gearing connecting the spring with one of the nail-plate feeding-rolls, and the escapement-wheel on the shaft of said roll, substantially as and for the purpose hereinbefore set forth.

14. The combination, substantially as hereinbefore set forth, of the outer cylinder, the oscillating inner cylinder, the ring or enlarged tube at the end of the inner cylinder, the loose drum, the pinion carried thereby, the coiled spring, the ratchet-wheel, the pawl on the outer cylinder acting on the ratchet-wheel at every alternate oscillation of the inner cylinder, the pawl carried by the inner cylinder and constantly engaging the ratchet-wheel, and gearing connecting the drum-pinion, and the rolls which feed the nail-plates.

15. The combination, substantially as hereinbefore set forth, of the oscillating cylinder, the nail-plate passage-way formed in bars or plates secured thereto, the feeding-rolls, the escape-wheel, the pallet-lever provided with the

cross-head or arms, and the stops for rocking said lever at each turn of the cylinder, for the purpose described.

16. The combination of the oscillating cylinder, the ratchet-wheel loosely mounted within the ring or shell at the end thereof, the drum also loosely mounted within said ring, the coiled spring secured at its opposite ends to the ratchet-wheel and drum, the pinion carried by the drum, the feed-roller driven from

said pinion, and the escapement mechanism, substantially as and for the purpose hereinbefore set forth.

In testimony whereof I have hereunto subscribed my name.

ELBERT C. TAYLOR.
